CLAIM

The ornamental design for a control unit for room automation and extension module as shown and described.

DESCRIPTION

FIG. 1 is a front view of a control unit for room automation and extension module.

FIG. 2 is a back view of a control unit for room automation and extension module.

FIG. 3 is a top view of a control unit for room automation and extension module.

FIG. 4 is a bottom view of a control unit for room automation and extension module.

FIG. 5 is a right side view of a control unit for room automation and extension module.

FIG. 6 is a left side view of a control unit for room automation and extension module.

FIG. 7 is a perspective top/front/left view of a control unit for room automation and extension module.

FIG. 8 is perspective bottom/front/right view of a control unit for room automation and extension module.

FIG. 9 is a front view of a control unit for room automation and extension module.

FIG. 10 is a back view of a control unit for room automation and extension module.

FIG. 11 is a top view of a control unit for room automation and extension module.

FIG. 12 is a bottom view of a control unit for room automation and extension module.

FIG. 13 is a right side view of a control unit for room automation and extension module.

FIG. 14 is a left side view of a control unit for room automation and extension module.

FIG. 15 is a perspective top/front/left view of a control unit for room automation and extension module; and,

FIG. 16 is perspective bottom/front/right view of a control unit for room automation and extension module.
